(57) **CLAIM**

The ornamental design for a shaver as shown and described.

DESCRIPTION

FIG. 1 is a front, right and top perspective view of a shaver, showing my new design.

FIG. 2 is a rear, left and bottom perspective view of the shaver of FIG. 1.

FIG. 3 is a front, right and top perspective view of an upper part of the shaver in FIG. 1.

FIG. 4 is a rear, left and bottom perspective view of FIG. 3.

FIG. 5 is a front elevation view of FIG. 3.

FIG. 6 is a rear elevation view of FIG. 3.

FIG. 7 is a left side elevation view of FIG. 3.

FIG. 8 is a right side elevation view of FIG. 3.

FIG. 9 is a top plan view of FIG. 3.

FIG. 10 is a bottom plan view of FIG. 3.

FIG. 11 is an enlarged view of detail 11 in FIG. 3.

FIG. 12 is a front, right and top perspective view of a lower part of the shaver in FIG. 1.

FIG. 13 is a rear, left and bottom perspective view of FIG. 12.

FIG. 14 is a front elevation view of FIG. 12.

FIG. 15 is a rear elevation view of FIG. 12.

FIG. 16 is a left side elevation view of FIG. 12.

FIG. 17 is a right side elevation view of FIG. 12.

FIG. 18 is a top plan view of FIG. 12.

FIG. 19 is a bottom plan view of FIG. 12; and,

FIG. 20 is an enlarged view of detail 20 in FIG. 12.

The dashed broken lines depict portions of the shaver that form no part of the claimed design. The dot-dash broken lines in FIGS. 3, 11, 12, and 20 depict the boundaries of the enlargements and form no part of the claimed design.

The upper and lower portions of the shaver are shown separately for convenience of illustration.

1 Claim, 20 Drawing Sheets
